CALCULATING MACHINE

Carl M. Friden, Oakland, Calif., assignor to
 Friden Calculating Machine Co., Inc., a corpora-
 tion of California

Application July 14, 1939, Serial No. 284,493

12 Claims. (Cl. 235—146)

My invention relates to calculating machines and is concerned more particularly with the provision of an improved machine of this character which is adapted for use in calculating operations involving a constant factor.

It is a general object of my invention to provide an improved calculating machine having constant factor mechanism which is differentially settable for adjustment to different selected values.

Another object of the invention is to provide an improved calculating machine of the character referred to in which an auxiliary differential mechanism is provided to adjust the usual selecting mechanism associated with the key board.

Another object of the invention is to provide an improved calculating machine of the character referred to in which the constant factor mechanism can be employed or not as desired by the operator.

Another object of the invention is to provide an improved calculating machine of the character referred to having auxiliary differential means for superseding the key board control of the machine in entering values therein.

Another object of the invention is to provide an improved calculating machine of the character referred to in which the constant factor mechanism is automatically brought into operation by control means which initiates a machine operation, and which can be used in both multiplication and division.

Another object of the invention is to provide an improved calculating machine of the character referred to in which the auxiliary constant factor mechanism can be brought into operation irrespective of whether keys of the keyboard are depressed.

Another object of the invention is to provide an improved calculating machine which is particularly adapted to calculate the distribution of overhead and other expenses.

Other objects and advantages of the invention will be apparent from the following description of a preferred embodiment thereof as illustrated in the accompanying drawings.

In the drawings:

Fig. 1 is a longitudinal sectional elevation through a calculating machine embodying my invention with the front end of the machine broken away.

Fig. 2 is a view similar to Fig. 1, but shows the front end of the machine only.

Fig. 3 is a transverse sectional elevation of

the keyboard as viewed from the front of the machine, the portion in elevation being taken in a location immediately in front of the zero keys of the keyboard, the portion in section being taken in the plane of the line 3—3 in Fig. 2.

Fig. 4 is a plan view of the front end of the machine with certain portions of the casing and keyboard mechanism broken away to illustrate the mechanism therebeneath.

10 Fig. 5 is a sectional elevation of the right side plate of the machine and the control and operating parts mounted thereon. The view is indicated by the line 5—5 in Fig. 4.

15 Fig. 6 is a sectional elevation of a portion of the plus-minus key mechanism and the division mechanism, the view being taken as indicated by the line 6—6 in Fig. 4.

20 Fig. 7 is a fragmentary sectional elevation of the left side plate and certain control mechanisms mounted thereon, the plane of the view being indicated by the line 7—7 in Fig. 4.

25 My invention is illustrated as embodied in the type of calculating machine having a uni-directionally operable actuator and reversible or bi-directionally operable numeral wheels, as disclosed in my co-pending application, Serial No. 724,482, filed May 8, 1934, now Patent No. 2,229,889, granted January 28, 1941. While certain features of my invention are adapted particularly for use in this type of machine, my invention is of general application and can be used in other types of calculating machines.

30 Selecting, actuating and accumulating mechanisms

35 The machine includes base 10 (Fig. 1) which supports casing 11 and has side frame plates 12, 13 (Figs. 1 and 4) mounted thereon. Side plates 12, 13 are connected by various cross frame brackets 16, 17, 18 and 19 (Fig. 1) which serve to mount various mechanisms referred to herein-after.

40 The accumulator comprises a series of reversible numeral wheels 21 (Fig. 1) in register carriage 22 which is mounted on brackets 16 and 19 by rollers 23 for endwise shifting movement laterally of the machine in either direction to various ordinal positions. The values to be introduced into numeral wheels 21 are selected by means of a plurality of banks or orders of settable numeral keys 24, each bank of which cooperates with selecting mechanism including a pair of spring-urged value selecting slides 25, 26 (Figs. 1-3) mounted for endwise movement by pivotally mounted link 27. Slides 25 and 26 are provided

with cam surfaces of varying inclination so that they can be set differentially in accordance with the value of a depressed numeral key. Slide 25 is associated with the "1" to "5" keys, and slide 26 is associated with the "6" to "9" keys.

At their rearward ends, slides 25, 26 of each order are connected to similar ten-tooth gears 28 slidably and non-rotatably mounted on a square shaft 29 suitably journaled in brackets 17 and 18, so that differential positioning of one of slides 25, 26 serves to similarly position the associated gear 28 with respect to the corresponding sets of stepped teeth of the associated actuating cylinder 30. Keys 24 of each bank are provided with a spring-urged latching slide 31 (Figs. 1 and 2) of conventional construction which maintains a depressed key in depressed position. Each slide 31 may be moved to key releasing position by operation of release key 32 (Fig. 2) or all the slides may be moved to key releasing position by means of bail 33 pivotally mounted as at 34.

Cylinders 30 (Fig. 1) for two orders of the machine are mounted on each actuating shaft 35 for cooperation with adjacent pairs of shafts 29. Shafts 35 have suitable bevel gear connections with transverse shaft 36 which is suitably journaled in side plates 12, 13.

Shaft 36 and shafts 35 are driven cyclically from motor 37 (Fig. 1) through clutch 38 (Fig. 5) which is driven by suitable gearing 39 from motor shaft 40. As explained in my said co-pending application, clutch 38 is engaged or disengaged by oscillation of spring-urged clutch pawl or dog 41 mounted for rotation with shaft 36 and with respect to ratchet 42 journaled on shaft 36 and driven by gearing 39. Clutch control lever 43 pivoted on side plate 13 determines engagement or disengagement of the clutch by releasing or engaging clutch dog 41 in the full cycle position thereof.

The values set in the machine by depression of keys 24 will be introduced into numeral wheels 21 by the cooperation of gears 28 with the teeth of cylinders 30 during cyclic operation of the clutch in a manner which will now be described. Each square shaft 29 (Figs. 1 and 3) extends rearwardly of the machine thru bracket 17 and has its rear end journaled in bracket 16. Intermediate brackets 16, 17, a spool 64 is slidably and non-rotatably mounted on each shaft 29 and has opposite bevel gears 46, 47 at its ends positioned for cooperation with numeral wheel gear 48 mounted at the lower end of numeral wheel shaft 49 journaled in frame 51 of carriage 22. Therefore, when one set of gears 46, 47 is engaged with gears 48, numeral wheels 21 will be rotated forwardly or reversely to register a number of increments equal to the value of the depressed keys 24 in the aligned banks of keys.

Plus and minus keys

Means are provided for selectively determining positive or negative registration on the numeral wheels in the form of plus key 56 (Fig. 6) and minus key 57 which are slidably mounted on auxiliary frame plate 58. Depression of either of keys 56, 57 serves to engage the clutch, close the motor circuit and select the sign character of the registration.

To enable the drive, keys 56, 57 have respective pins 59 in operative relation with suitable cam surfaces on clutch actuating slide 61 mounted for endwise movement on plate 58. To effect control

of the clutch by such movement, pin 62 on the upper arm of clutch control lever 43 (Figs. 5 and 6) abuts the rear end of slide 61, so that rearward movement of slide 61 oscillates lever 43 in a clockwise direction as viewed in Fig. 5 to release clutch dog 41 for engagement with ratchet 42 on shaft 36.

To close the motor circuit, slide 61 is slotted for engagement, pin 63 (Figs. 5 and 6) carried by lever 64 (Fig. 5) which is pivoted on side plate 13 and connected at its lower end with lever 66 also pivoted on plate 13. Lever 66 has a suitable insulated pin in overlapping relation with spring mounted contact 67 normally spaced from similar contact 68. Upon clutch-engaging movement of slide 61, levers 64 and 66 are rocked to move contact 67 into engagement with contact 68.

To determine the sign character of the registration, plus and minus keys 56, 57 (Fig. 6) have respective rollers 71, disposed in operative relation with opposed cam surfaces 72 on plus-minus slide 73. Slide 73 is mounted for endwise movement at its front end by link 74 and at its rear end by arm 76 on shaft 77 (Figs. 1 and 6) which is suitably journaled in slide plates 12, 13. Shaft 77 carries transversely extending strap 78 (Fig. 1) which is positioned between gears 46, 47 so that rocking movement of shaft 77 under control of plus-minus slide 73, serves to determine engagement of gears 46 or 47 with numeral wheel gears 48 (Fig. 1) or to determine the disengagement thereof as in the position shown. The gears 46, 47 may be resiliently held in their central neutral position by suitable centralizing means of the character shown in said application.

Thus depression of plus key 56 by meshing gears 46, 48 and enabling the drive determines one or more positive registrations of the value set in the keyboard on numeral wheels 21. Similarly, depression of key 57 determines one or more negative registrations of such values by meshing gears 47, 48.

Accumulator transfer mechanism

Means of conventional construction are provided for carrying from order to order in the accumulator when the registration of a numeral wheel changes from zero to nine or vice versa. For this purpose, each numeral wheel shaft 49 (Fig. 1) carries a single tooth gear 81 in operative relation with transfer lever 82 suitably pivoted on frame 51. Each lever 82 has an end extending downwardly into operative relation with collar 84 of the next higher order of the machine, which carries gear 86 normally disposed out of the path of single tooth actuator 87 on shaft 35. When numeral wheel 21 of one order passes from nine to zero or vice versa, single tooth gear 81 rocks lever 82 to position gear 86 of the next higher order in the path of the associated transfer actuator 87. Thus, the transferred increment is introduced through either gear 46 or 47 of next higher order depending upon setting of the machine for addition or subtraction. The transfer mechanism is of the type fully disclosed in my said co-pending application.

Revolutions counter

A revolution counter is also provided to register positively or negatively the number of actuations of accumulator numeral wheels 21. Counter numeral wheels 91 (Fig. 1) are suitably journaled in carriage 22 and are driven by actuator 92 on shaft 93 to register the number of positive and

negative registrations on numeral wheels 21 as fully disclosed in said application.

Carriage shift mechanism

Means of conventional construction are provided for shifting the carriage in either direction from one ordinal position to another by power driven means controlled by manually operable keys. Carriage 22 (Fig. 1) has toothed rack 101 suitably mounted along the rear side thereof and the teeth of the rack are adapted for engagement by similar opposite shift pins 102 on shift gear 103 suitably journaled on bracket 16. Shift gear 103 is rotated selectively in either direction through suitable gearing 104 to shift the carriage through any desired number of ordinal spaces, by means including normally disabled drive connections 106 with one or more of shafts 35, each drive connections being controlled by a suitable linkage including rod 107 and arm 108, operated from respective shift keys 109, 110 (Fig. 5). The carriage shift mechanism is of the type disclosed and claimed in my co-pending application Serial No. 27,338, filed June 19, 1935.

Division mechanism

Division mechanism is provided of the general character disclosed in my co-pending application Serial No. 35,619, filed August 16, 1935, and the mechanism operates in the conventional manner to repeatedly subtract the divisor from the aligned order of the divided until an overdraft occurs. The overdraft is corrected, the carriage shifted, and subtractive operation re-initiated, until the desired number of quotient digits are obtained in the revolutions counter. Only those conventional parts of the division mechanism which cooperate in providing the instant invention will be described.

Division control lever 121 (Fig. 6) is pivoted at 122 on auxiliary plate 58 and has its lower end in operative relation with roller 123 on division setting slide 124. To provide for endwise movement thereof, slide 124 is slotted to engage studs 126 on plate 58. Spring 127 tensioned between slide 124 and plate 58 urges slide 124 to its forward position illustrated in Fig. 6. At its rear end, slide 124 carries roller 128 in abutting relation with a depending part of arm 131 of connecting lever 132, which set the machine for division and enables the drive as later described. Lever 132 is pivoted at 133 on arm 134 which is supported pivotally at 135 on plate 58. Arm 134 is oscillated by cam 136 in controlling machine operations during division as fully described in said application Serial No. 35,619.

From the foregoing description, it is seen that rearward movement of division setting slide 134 serves through roller 128 to rock lever 132 in a clockwise direction about its pivot 133 and such clockwise movement serves to connect lever 132 with plus-minus slide 73. For this purpose the rearward arm of lever 132 is provided with notch 137 adapted to engage pin 138 which is suitably mounted on plus-minus slide 73. The movement of bell crank 132 to engage notch 137 with pin 138 serves to move slide 73 forwardly by virtue of inclined edge 139 adjacent notch 137, thereby rocking shaft 77 and meshing gears 47, 48 so that the machine is set for subtraction. This action occurs because of the position of pivot 133 for connecting lever 132 as determined by control cam 136.

The clockwise movement of lever 132 (Fig. 6) serves to condition the clutch for engagement

and the motor circuit for closing. At its front end lever 132 is pivotally connected with link 141 having its upper end pivotally connected to the rearward horizontal arm of bell crank 142 which is pivotally mounted at 143 on plate 58. The vertical arm of bell crank 142 is in abutting relation with pin 144 adjustably mounted on clutch actuating slide 61. Spring 146 tensioned between bell crank 142 and plate 58 maintains bell crank 142, link 141 and connecting lever 132 in the positions shown when division setting slide 124 is also in its idle position. Thus, clutch actuating slide 61 is free to be moved under the influence of the other operating controls.

From the described linkage it is seen that clockwise motion of lever 132 serves thru link 141 and bell crank 142 to move clutch actuating slide 61 rearwardly to rock control lever 43 (Fig. 5) to clutch engaging position as previously described. However, the clutch is not engaged because of the action of special mechanism brought into play by division setting slide 124.

Pin 151 (Figs. 5 and 6) on slide 124 lies in front of arm 152 (Fig. 5) provided at 153 on side plate 13. Pawl 154 pivoted on arm 152 has its upper arm held against a suitable lateral extension of arm 152 by spring 156. Spring 156 also serves to hold arm 152 and pawl 154 in the position shown with nose 157 of pawl 154 spaced from its cooperating notch 158 in clutch dog 41.

Rearward movement of slide 124 (Fig. 6) through pin 151 serves to rock arm 152 and pawl 154 to engage nose 157 with notch 158 so that clutch dog 41 is maintained in clutch disengaging position irrespective of the release thereof by control lever 43. Subsequently, the return movement of slide 124 forwardly, permits engagement of the clutch. Thus, the clutch is not engaged prematurely so that if the motor should be coasting from a previous operation no harm is done.

It will be recalled also that the rearward movement of slide 61 serves through levers 64, 66 (Fig. 5) to move contact 67 to circuit closing position. However, the circuit is not closed by this movement of contact 67 but is merely conditioned for closing by virtue of the movement of insulated pin 151 (Figs. 5 and 6) mounted on division setting slide 124 and engaging the extended end of contact 68. When slide 124 moves rearwardly, pin 151 moves contact 68 out of circuit closing position and the circuit is merely conditioned for energization. Subsequent restoration of control lever 121 and division setting slide 124 upon release of lever 121 allows contact 68 to return to normal position and thereby engage contact 67 to start the division operation.

However, before the division operation begins, i. e., before return of lever 121 to its normal position, latch means becomes effective to latch the settable parts in their above described adjusted positions for the division. The latch means may be associated with connecting lever 132 to maintain said lever in its adjusted active position until the end of the division operation. Adjacent its rear end, lever 132 (Figs. 5 and 6) has flat bottomed pin 161 projecting therefrom in operative relation with latch lever or member 162 (Fig. 5) pivoted at 163 on side plate 13 and urged in a clockwise direction as viewed in Fig. 5 by spring 164. When lever 132 is moved by setting slide 124, pin 161 moves upwardly rocking latch member 162 until pin 161 rises above latching face 166 on member 162. Spring 164 then becomes effective to move face 166 beneath pin

161 whereby lever 132 and the parts adjusted thereby are maintained in operative relation. Thus, arm 134, connecting lever 132, plus-minus slide 73 and latch member 162 are latched together for movement as a unit under control of cam 136, slide 73 having been adjusted to its minus or subtracting position. Latch 162 may be moved to inoperative position at the end of a division operation by any suitable means, for example, by the means disclosed in said application Serial No. 35,619.

Constant factor mechanism

In many calculating operations, one of the factors is constant through one series of calculations although varying from one series to the next. For example, many interest and percentage calculations are carried on with a constant multiplicand. Many division problems employ a constant dividend or a constant divisor, as for example in distributing the cost of overhead and other expenses. Moreover, it is frequently desirable to perform intermediate calculations between calculations using a constant factor. Heretofore, the keyboard has been utilized for all types of selective setting of selection mechanism, and during operations such as those referred to above, this condition has entailed repeated entry of the same number in the selecting mechanism by use of the keyboard.

In accordance with the instant invention, an auxiliary setting control means is provided for the selection mechanism which can be employed instead of the keyboard, when a factor is to be used repeatedly in a series of multiplying or dividing operations.

Referring to Figs. 1-4, respective selection slides 25 and 26 of each order are provided at their lower edges with cam surfaces 171 leading to seats 172 formed therein for cooperation with respective rollers 173 on selecting arms 174, 176. Arms 174, 176 of each order have two movements, one a differential movement controlled by the setting means of the constant factor mechanism, and the other an operating movement to move the selecting arms and position the selecting slides 25 and 26 associated therewith.

To enable differential adjustment of the respective selecting arms 174, 176 (Figs. 1, 2 and 4) the arms are pivoted at 177 to the associated slides 178, 179 which are slotted for engagement with cross rods 181 to be guided for movement parallel to the movement of selection slides 25 and 26. At their forward ends, each set of slides 178, 179 carry respective rollers 182 for cooperation with cams 183, 184 secured on sleeve 186. Disc 187 mounted on sleeve 186 has setting handle 188 projecting through the casing 11. Sleeves 186 are pivotally mounted in end to end relation on transverse rod 189 extending between side plates 12 and 13.

The pivotal mounting of disc 187 and the associated assembly provides for adjustment thereof by means of handle 188 through one to nine steps from the position shown to display the numerals inscribed on flange 191 of disc 187 through the aligned sight opening 192 of the casing. The adjusted position of the disc 187 and the associated parts are maintained by spring-urged pawl 193 (Fig. 2) engageable with seats 194 in disc 187.

The counterclockwise movement of the disc 187 produces similar movement of cams 183 and 184 to correspondingly position the respective slides 178, 179 and selecting arms 174, 176. It will be seen in Fig. 2 that cam 183 is provided with cam

rise 196 which becomes effective immediately upon movement of the parts from the position shown in Fig. 2 to set slide 178 selectively in its "one" to "five" positions. The cam rise 196 is followed by a concentric portion 197 so that further turning of the assembly has no effect on slide 178.

Cam 184 in the angular portion thereof corresponding to cam rise 196 is provided with concentric portion 198 which is followed by cam rise 199, corresponding to the concentric portion 197 of cam 183. In this manner the initial five steps of movement of disc 187 will serve to set slide 178 and selecting arm 174, and the succeeding sixth to ninth steps of movement operate through cam rise 199 to set slide 179 and selecting arm 176. Inasmuch as both gears 28 can be active at the same time, the fact that the slide 178 remains in active position while the slide 179 is being set does not effect the operation of the machine.

The movement of slides 178, 179 serves to position the respective rollers of the selecting arms 174, 176 differentially with respect to the associated cam surface 171 of the associated selecting slides 25 and 26, so that rocking movement of selecting arms 174, 176 in a counterclockwise direction will engage the rollers 173 with the respective cam surfaces 171 and effect differential positioning of the selecting slides 25, 26.

Means is provided under the control of the division mechanism for effecting the actuating movement of the selecting arms 174, 176, and for this purpose the selecting arms 174 (Figs. 1 and 4) are provided with pins or rollers 201 cooperatively related with cam surface 202 of setting arms 203 secured on transverse shaft 204. Two setting arms 203 are provided in each order of the machine, one for selecting arm 174 and one for selecting arm 176, and all of the setting arms 203 are interconnected by transverse rod 206 and suitable spacing collars 207 interposed between the ends of the arms.

Preferably, the setting movement of the division control means is utilized when the constant factor mechanism is enabled to adjust the selecting slides in accordance with the differential setting of the constant factor mechanism and to release any depressed keys which might interfere with such differential position.

To release the depressed keys, transverse rod 206 (Fig. 4) carries link 208 (Figs. 4 and 7) which extends forwardly and is hooked over key release bail 33 so that clockwise movement of shaft 204 as viewed in Fig. 1 will result in rearward movement of link 208 and effect a key releasing movement of the bail 33, and as explained later the bail is latched in this key releasing position.

At its right hand end, shaft 204 (Figs. 4 and 5) has arm 209 supported freely thereon. The hub of arm 209 extends through plate 13 and has its reduced end formed as part of a clutch connection with clutch collar 210 slidably keyed on shaft 204 and spring-urged to inactive position as shown. To shift collar 210 and thereby connect shaft 204 and arm 209, control key 211 (Figs. 4 and 5) is suitably mounted for endwise movement on side plate 13 and provided with a suitable latch notch for engagement with stud 211a whereby the key can be latched in depressed position. The lower cam end of key 211 is operatively related to lever 212 which is engaged with collar 210 by suitable pin and grooves to control its adjusted position. The arrangement of the parts is such that depression of key 211 effects clockwise movement of lever 212 as viewed

In Fig. 4 to shift collar 210 into engagement with the hub of arm 209 to connect the arm to shaft 204.

Arm 209 provides a connection for enabling the constant factor mechanism automatically upon initial movement of the division lever to set the machine for division, and before the division operation is actually begun. For this purpose, arm 209 carries pin 213 (Figs. 4 to 6) disposed in front of shoulder 214 of division setting slide 124 so that rearward movement of this slide, that is, to the left in Fig. 6, will cause clockwise rocking of arm 209 and shaft 204 as viewed in Fig. 5.

Latch means are provided for latching the selecting mechanism in active position, and this means is preferably disabled except when the division mechanism is active. Arm 209 (Figs. 5 and 6) carries flat-sided pin 216 for cooperation with latch lever 217 (Fig. 6) pivoted at 218 on plate 58 and having its rearward end normally held elevated by roller 219 on bellcrank 132. Lever 217 is urged in a counterclockwise direction by spring 221 and can move in that direction to active position upon clockwise movement of bellcrank 132 to lower roller 219.

Such clockwise movement of bellcrank 132 occurs during setting of the machine for division so that simultaneously with such setting, the values entered in the constant factor mechanism are set into the selecting slides and the mechanism is latched to maintain this setting throughout the division operation. At the end of the division operation when the latch lever 162 (Fig. 5) is released and bellcrank 132 (Fig. 6) is free to return to position shown in Fig. 6, latch lever 217 is moved to inactive position and releases the constant factor mechanism so that it also becomes inactive.

When it is desired to use the constant factor mechanism for other operations than division a separate control is provided.

Manually operable key 226 (Fig. 7) is slotted to engage stud 227 so that the key can be displaced against the urging of spring 228 secured thereto and to latching stud 229 on plate 12. Stud 229 is disposed for engagement by latch seat 231 in key 226 to maintain the key depressed. At its lower end key 226 is provided with pin 232 engaging an elongated slot in link 233 pivoted at its other end 234 to arm 236 on the left hand end of shaft 204. Thus, depression of key 226 serves to rock shaft 204 and enable the constant factor mechanism as described.

While I have shown and described a preferred embodiment of the invention, the invention is capable of both variation and modification so that its scope should be limited only by the appended claims.

I claim:

1. In a calculating machine, selecting mechanism, a keyboard for controlling said mechanism, normally ineffective differentially settable means for superseding the control of said keyboard over said selecting mechanism, machine operation control means including an operation initiating key, a normally disabled control train from said key to said settable means for causing movement of said settable means to effective position, and control means for enabling said train whereby upon operation of said key said settable means is moved to effective position.

2. In a calculating machine, selecting mechanism, a keyboard for controlling said mechanism, normally ineffective differentially settable means for superseding the control of said key-

board over said selecting mechanism, machine operation control means including an operation key having one movement to condition the machine for operation and another movement to initiate operation of the machine, and means operated by said key during said one movement thereof for enabling said settable means to thereby set one factor of the calculation into the selecting mechanism during conditioning of the machine for operation.

3. In a calculating machine, selecting mechanism, a keyboard for controlling said mechanism, normally ineffective differentially settable means for setting said selecting mechanism, division control mechanism for said machine including a control member having an inactive position and an active position, means controlled by said mechanism for moving said settable means to effective position, means for latching said settable means in effective position, said latching means being spring-urged to latching position, and means controlled by said member in the inactive position thereof for restraining said latching means.

4. In a calculating machine having an accumulator, ordinarily arranged differential selecting mechanism having the orders thereof arranged transversely of the machine, a plurality of longitudinally extending banks of keys for cooperation with the respective orders of said selecting mechanism, a series of ordinarily arranged differentially settable auxiliary control means for said selecting mechanism arranged in front of said bank of keys, and operating connections from each of said auxiliary setting means to the associated order of said selecting mechanism, said connections being selectively operable to cause setting of said selecting mechanism in accordance with values introduced into said control means.

5. In a calculating machine, ordinarily arranged differential selecting mechanism including a pair of differentially movable selecting elements in each order, a bank of keys for cooperation with each order of said selecting mechanism, certain of the keys of a bank being operatively related to one element only of the associated pair of elements and the others of the keys of a bank being operatively related only to the other element of said associated pair, a series of differentially settable dials, one dial being arranged in front of each bank of keys, a pair of cams associated with each dial, and a selectively operable slide from each of said cams to one of said selecting elements, one of said cams having a cam rise disposed for operation during the initial portion of the setting of said dial and being inactive during the last portion of the setting movement thereof, and the other of said cams being inactive during said initial portion of the setting movement of said dial and having a cam rise disposed for operation during said last portion thereof.

6. In a calculating machine having an accumulator, the combination with ordinarily arranged differential selecting mechanism for said accumulator, and ordinal banks of keys for setting said selecting mechanism; of auxiliary, ordinarily arranged control means for said selecting mechanism, including manually operable differentially settable means associated with each order of said selecting mechanism for superseding the control of the related banks of keys and for setting said associated order of said selecting mechanism, said settable means in each order being individ-

ually adjustable to represent values from "zero" to "nine" and said settable means having an idle position in which it is settable to represent differential values but is ineffective to cause registering of such values and also having an active controlling position in which the values set therein are also set in said selecting mechanism to control registering in said accumulator.

7. In a calculating machine having an accumulator, the combination with ordinally arranged differential selecting mechanism for said accumulator, ordinal banks of keys for setting said selecting mechanism, and means for latching said keys in depressed position; of auxiliary, ordinally arranged control means for said selecting mechanism including manually operable differentially settable means associated with each order of said selecting mechanism for superseding control of the related banks of said keys and for setting said associated order of said selecting mechanism, said settable means in each order being individually adjustable to represent values from "zero" to "nine" and said settable means having an idle position in which it is settable to represent differential values but is ineffective to cause registering of such values and also having an active controlling position in which the values set therein are also set in said selecting mechanism to control registering in said accumulator, and means brought into play with said settable means in said active controlling position for rendering said latching means ineffective.

8. In a calculating machine having an accumulator, the combination with ordinally arranged differentially settable selecting mechanism for said accumulator, and keys for controlling the setting thereof; an auxiliary control means for said selecting mechanism, including manually operable differentially settable means arranged in ordinal relation with each order thereof cooperating with an associated order of said selecting mechanism, each order of said settable means being individually adjustable by manual setting movement to represent values from "zero" to "nine," said settable means having an idle position in which it is settable to represent said differential values but ineffective to cause registering of said values in the machine and also having an active controlling position in which the values set therein are also set in said selecting mechanism to control registering in said accumulator, means for moving said differential settable means to its active controlling position, and means for latching said settable means in said active controlling position.

9. In a calculating machine having an accumulator, ordinally arranged differentially settable selecting mechanism, a keyboard for controlling said mechanism, normally ineffective differentially settable means arranged in ordinal fashion and related order to order with said selecting mechanism for superseding the control of said keyboard over said selecting mechanism, said settable means having an idle position in which it is settable to represent differential values but is ineffective to cause registering of said values and also having an active controlling position in which the values set therein are also set in said selecting mechanism to control reg-

istering in said accumulator, machine operation control means including an operation initiating key, and means operated by said key for moving said settable means to its active position.

5 10. In a calculating machine having an accumulator, ordinally arranged differentially settable selecting mechanism, a keyboard for controlling said mechanism, normally ineffective differentially settable means arranged in ordinal fashion and related order to order with said selecting mechanism for superseding the control of said keyboard over said selecting mechanism, said settable means having an idle position in which it is settable to represent differential values but is ineffective to cause registering of said values and also having an active controlling position in which the values set therein are also set in said selecting mechanism to control registering in said accumulator, machine operation control means including an operation initiating key, means operated by said key for moving said settable means to its active position, and means controlled by said operation initiating key for rendering said keyboard ineffective when said settable means is active.

15 11. In a calculating machine having an accumulator, ordinally arranged selecting mechanism, a keyboard for controlling said mechanism, normally ineffective differentially settable means arranged in ordinal fashion and related order to order with said selecting mechanism for superseding the control of said keyboard over said selecting mechanism, said settable means having an idle position in which it is settable to represent differential values but is ineffective to cause registering of said values and also having an active controlling position in which the values set therein are also set in said selecting mechanism to control registering in said accumulator, means for dividing an amount entered in said accumulator by an amount set into said selecting mechanism including a member movable to initiate a division operation, and means controlled by said member upon movement thereof for moving said settable means to its active position.

20 12. In a calculating machine having an accumulator, ordinally arranged selecting mechanism, a keyboard for controlling said mechanism, normally ineffective differentially settable means arranged in ordinal fashion and related order to order with said selecting mechanism for superseding the control of said keyboard over said selecting mechanism, said settable means having an idle position in which it is settable to represent differential values but is ineffective to cause registering of said values and also having an active controlling position in which the values set therein are also set in said selecting mechanism to control registering in said accumulator, means for dividing an amount entered in said accumulator by an amount set into said selecting mechanism including a member movable to initiate a division operation, a normally disabled control train between said member and said settable means for causing movement of said settable means to active position, and manually settable control means for enabling said train.
